UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

PEDAL-DOOR OR THE LIKE.

1,164,100.

Specification of Letters Patent. Patented Dec. 14, 1915.

Application filed March 18, 1910. Serial No. 550,218.

To all whom it may concern:

Be it known that I, PAUL BROWN KLUGH, citizen of the United States, residing at Chicago, in the county of Cook and State of Illinois, have invented a certain new and useful Improvement in Pedal-Doors or the like, of which the following is a full, clear, concise, and exact description, reference being had to the accompanying drawings, forming a part of this specification.

My invention relates to mechanism for closures for recesses, such as pedal doors and the like, and in its preferred form, is adapted for use in combination with a closure for a recess within which an extensible member is mounted, which closure is to be opened to permit the extension of said member from within said recess to the exterior, whereupon the closure is again allowed to assume its normal position of closing the recess, means being provided whereby the extensible member may remain in its extended position even though the closure is in its normal closed position. In the preferred form of my invention, this closure is made in two hinged parts, and is under the control of an arm actuated by a lever, which lever, when operated, moves the closure to open the recess, and which closure may then again be closed into its normal position.

I will describe my invention more in detail by reference to the accompanying drawings, illustrating one embodiment thereof, in which—

Figure 1 is a side view, partly in section, of my improved mechanism; Fig. 2 is a detail view of the lever mechanism; and Fig. 3 is a rear view of the closure in its normal or closed position, with the lever mechanism removed.

Referring more particularly to Fig. 1, in which I have shown the invention as applied to a piano player, or player piano, I show the lower portion of a player piano, 1, with the base of which bellows 2 is mounted, which bellows is adapted for actuation by means of pedals 3, which pedals and bellows, are more clearly set forth in my Patent No. 874,408, issued December 24, 1907. The pedals are adapted for extension into the dotted position shown in Fig. 1, when in use, at which time the arms 4 and 5 extend through slots such as 6, 6, to permit the pedals to operate the bellows. When the pedals are not in use, they are placed in a

position indicated by full lines in Fig. 1, directly against the bellows mechanism. A removable panel 25 is placed vertically within the base of the piano in front of bellows 2. The panel 25 is held at its top when in normal position as shown in Fig. 1, by one or more spring catches or latches 26. The panel 25 is also slotted at its top as shown at 27. Panel 25 forms a recess for the bellows and pedals and has an aperture 65 through which the pedals may be folded and unfolded. The recess within which these pedals are mounted is adapted to be closed by a closure 7, hinged at 8, and formed of two hinged parts, 9 and 10, hinged together 70 at 11, the closure 7 being supported by the portion of the panel 25 immediately above the part 9 and said closure 7 closing said aperture in said panel 25. Stops 12, 12 limit the movement of the closure. The closure is also provided with a catch 13, and a spring 14, which, by virtue of the spring action, holds the closure in its normal position, when it is once brought in that position. In order to withdraw the pedals, the 80 closure must be opened, and while the pedals remain withdrawn, the closure may again be closed, thus to present a good appearance, and can remain so until the pedals are again to be placed within the recess, as will be apparent.

In order to properly open the closure, I provide an L-shaped lever 15, pivoted at 16, in a bracket 17, and associate with this lever 15 a connecting link 18, which is hinged to 90 a lever 19. The lever 19 is pivoted at 20, and has a handle 21, the free end of the lever moving within a guide 22. Now, when the right hand extremity of the lever 19, as shown in Fig. 2, is drawn toward the operator, the lever 15 occupies the dotted position shown in Fig. 1, and opens the closure, whereupon the pedals may be withdrawn. Then, the closure is again placed in its normal position, the slots 6 accommodating the 100 extensible members or pedals, and the spring 14 holds the closure in place. When it is desired to again replace the pedals, the lever 19 is again actuated to open the closure, after which the pedals are replaced, and the 105 closure moves to occupy its normal position, as shown in full lines in Fig. 1.

While I have herein shown and particularly described the preferred embodiment of my invention, I do not desire to limit my- 110

self to the precise construction and arrangement as herein set forth, but

Having thus described my invention, what I claim as new and desire to secure by Letters Patent is:

- 5 1. A musical instrument comprising in combination, a casing, a support formed by a portion of said casing, a swinging closure comprising a depending upper section pivoted at its upper edge to said support and a depending lower section hinged at its upper edge to said upper section, a lever arranged to act upon the upper section of said closure, a rod connected directly to said lever for operating the same, said rod passing through said casing, and means for operating said rod connected directly therewith. 10
- 10 2. In a device of the class specified, a support, a swinging pedal door comprising a depending upper section pivoted to said support at its upper edge and a depending lower section hinged to said upper section at its upper edge, a lever arranged to act upon said upper section, a bracket supported by the instrument and supporting said lever, a link connected to the lever and extending through the front board of the instrument, and means for operating said link. 15
- 15 3. In a device of the class specified, a support, a swinging pedal door comprising a depending upper section pivoted to said support at its upper edge and a depending lower section hinged to said upper section at its upper edge, a lever arranged to act upon the upper section, a bracket supported by the instrument and supporting said lever, a link connected to the lever and extending through the front board of the instrument, and a pivoted lever for operating said link. 20
- 20 4. In a device of the class specified, a support, a swinging pedal door comprising a depending upper section pivoted to said support at its upper edge and a depending lower section hinged to said upper section at its upper edge, a swinging lever arranged in substantially vertical position in the rear of said door and having a forwardly bent end arranged to act upon the rear of the upper section of the pedal door, a bracket supported by the key bed and supporting said lever, the lever being pivoted between its ends, a link pivotally connected to the upper end of said lever and extending through the front board of the casing, and a lever to operate said link. 25
- 25 5. In a device of the class specified, a support, a swinging pedal door supported thereby, a vertically arranged lever having a bent end arranged to act upon said pedal door to swing the same open, a second support for said lever, said second support being carried by the frame of the instrument independent of the last mentioned support, and means for operating said lever. 30
- 30 6. In a musical instrument, a closure in the instrument case comprising a pivotally-supported depending upper section and a depending lower section hinged thereto at its upper edge, a lever arranged to act upon and swing the upper section of said closure, and means for actuating said lever comprising a link attached thereto and a second lever connected with said link. 70
- 35 7. In a musical instrument, the combination with a casing, a removable panel comprised therein, and a closure attached to said panel, of a closure-moving device secured within said casing to act upon said closure, and means arranged without said casing and connected with said device, whereby operation of said means actuates said device to move said closure; said device being free from attachment with said panel. 75
- 40 8. In a musical instrument, a key-bed, a removable front wall portion below said key-bed, a closure attached to said wall portion, and a closure-moving device secured below said key-bed free from attachment with said wall portion to act upon and move said closure. 80
- 45 9. In a musical instrument, a key-bed, a removable front wall below said key-bed, a closure attached to said wall, and a closure-moving device secured below said key-bed behind said wall to act upon and move said closure; said device being free from attachment with said wall. 90
- 50 10. In a musical instrument, the combination with a key-bed, a removable front wall below said key-bed, and a closure attached to said wall, of a lever pivotally supported beneath said key-bed behind said wall, and means connected with and extending forwardly from said lever to a position forward of said wall by which said lever may be actuated to move said closure; said lever being free from attachment with said wall. 100
- 55 11. In a musical instrument, the combination with a key-bed, a removable front wall below said key-board, and a closure attached to said wall, of a bracket secured beneath said key-bed behind said wall, a vertically-swinging lever supported by said bracket, a horizontally-swinging lever secured beneath said key-bed forward of said wall, and means connecting the two said levers whereby operation of said lever forward of said wall actuates said lever behind said wall to move said closure. 110
- 60 12. In a musical instrument, the combination with a key-bed, a removable front wall below said key-bed, and a closure attached to said wall, of a bracket secured beneath said key-bed behind said wall, a vertically-swinging lever supported by said bracket, a horizontally-swinging lever secured beneath said key-bed forward of said wall, and means connecting the two said levers whereby operation of said lever forward of said wall actuates said lever behind said wall to move said closure. 115
- 65 13. In a musical instrument, the combination with a key-bed, a removable front wall below said key-bed, and a closure attached to said wall, of a bracket secured beneath said key-bed behind said wall, a vertically-swinging lever supported by said bracket, a horizontally-swinging lever secured beneath said key-bed forward of said wall, and means connecting the two said levers whereby operation of said lever forward of said wall actuates said lever behind said wall to move said closure. 120
- 70 14. In a musical instrument, the combination with a key-bed, a removable front wall below said key-bed, and a closure attached to said wall, of a bracket secured beneath said key-bed behind said wall, a vertically-swinging lever supported by said bracket, a horizontally-swinging lever secured beneath said key-bed forward of said wall, and means connecting the two said levers whereby operation of said lever forward of said wall actuates said lever behind said wall to move said closure. 125
- 75 15. In a musical instrument, the combination with a key-bed, a removable front wall below said key-bed, and a closure attached to said wall, of a bracket secured beneath said key-bed behind said wall, a vertically-swinging lever supported by said bracket, a horizontally-swinging lever secured beneath said key-bed forward of said wall, and means connecting the two said levers whereby operation of said lever forward of said wall actuates said lever behind said wall to move said closure. 130

said wall to move said closure; said bracket, the two said levers, and said means comprising closure-moving apparatus which is free from attachment with said removable wall.

5 13. A musical instrument comprising in combination, a removable panel having an opening therein, a closure for said opening pivoted to said panel, a pivoted lever for operating said closure, a link directly connected to said lever and an operating lever connected directly to said link.

10 14. In a device of the class described in combination, a piano having a keyboard, a removable panel in said piano mounted beneath said keyboard and having an opening therein, a closure for said opening pivoted to said panel, a bracket carried by the piano independent of said panel, a lever pivoted to said bracket and having one end adjacent 15 said closure for operating the same, a link or rod connected directly to the upper end of said lever, and a manually operated lever connected directly to said rod.

15 15. In a musical instrument in combination, a closure in the instrument case comprising a pivotally supported depending upper section and a depending lower section hinged thereto at its upper edge, a lever arranged to act upon said swinging upper section 20 of said closure, a bracket mounted independently of said closure in which said lever is pivoted, and means for actuating said lever comprising a link attached thereto and a second lever connection with said 25 link.

30 16. In a musical instrument in combination, a keybed, a vertical panel provided with an aperture mounted beneath said keybed, a closure for said aperture comprising 35 a pivotally supported depending upper section and a depending lower section hinged thereto at its upper edge, a lever arranged to act upon said swinging upper section of said closure, a bracket attached to the under 40 side of said keybed and independent of said panel in which said lever is pivoted, and means for actuating said lever comprising a link attached thereto, and a second lever connected with said link.

45 17. In a musical instrument in combination, a keybed, a bracket attached to the under side of said keybed, a removable vertical panel provided with an aperture, said panel being mounted beneath said keybed in front of said bracket and independently thereof, a hinged closure for said aperture, a lever mounted in said bracket for operating said closure, a link carried close to said keybed connected at one end to said lever and running forward toward the front of the keybed, and a second lever mounted underneath the keybed near its outer edge connected to the other end of said link, said link and said second mentioned lever being independent of said panel.

50 18. In a musical instrument in combination, a keybed, a bracket attached to the under side of said keybed, a removable vertical panel provided with an aperture, said panel being mounted beneath said keybed in front of said bracket and independently thereof, a hinged closure for said aperture, a vertical lever mounted in said bracket for operating said closure, a link carried close to said keybed connected at one end to said lever and running forward toward the front of the keybed, and a second lever horizontally pivoted to said keybed near its outer edge connected to the other end of said link, said link and said second mentioned lever being independent of said panel.

55 19. A musical instrument comprising in combination, a panel provided with an aperture, a swinging closure comprising two sections, the first of which is hinged to said panel and the other of which is hinged to said first section, a lever arranged to act on said first section, a rod connected directly to said lever for operating it, said rod passing through said panel, and means for operating said rod connected directly thereto.

60 In witness whereof, I hereunto subscribe my name this 17th day of January A. D., 1910.

PAUL BROWN KLUGH.
